UNITED STATES PATENT OFFICE.

GEORGE W. HUBER, OF PHILADELPHIA, PENNSYLVANIA, ASSIGNOR, BY
MÉSNE ASSIGNMENTS, TO HORACE A. EFFRIG AND THADDEUS S.
KRAUSE, OF SAME PLACE.

MACHINE FOR COMPRESSING POWDERED OR GRANULAR SUBSTANCES.

SPECIFICATION forming part of Letters Patent No. 593,100, dated November 2, 1897.

Application filed May 25, 1896. Serial No. 592,968. (No model.)

To all whom it may concern:

Be it known that I, GEORGE W. HUBER, a citizen of the United States, residing in Philadelphia, Pennsylvania, have invented certain 5 Improvements in Machines for Compressing Powdered or Granular Substances, of which the following is a specification.

The object of my invention is to provide for the use of druggists and others a cheap 10 and simple but effective machine for compressing powdered or granular materials into the form of disks or tablets. This object I attain in the following manner, reference being had to the accompanying drawings, in 15 which—

Figure 1 is a view, partly in section and partly in side elevation, of a machine constructed in accordance with my invention, showing the parts in position for the reception 20 of the powdered or granular material. Fig. 2 is a similar view showing the parts in position for compressing said material. Fig. 3 is a view, partly in plan or top view and partly in section, illustrating the parts of the 25 machine in position for expelling the compressed tablet. Fig. 4 is a sectional view, partly in elevation, of part of the machine, illustrating one of the features of construction of the same; and Figs. 5 and 6 are views, 30 partly in section and partly in elevation, of the feeding device for the machine.

The base or bed plate of the machine is represented at 1, this base having a flat top which serves for the support of a sliding plunger-head 2 and a sliding mold-head 3, said 35 plunger-head having secured thereto a plunger 4, and the mold-head having secured to it a tubular mold-block 5, to which fit snugly both the plunger 4 and another plunger 6, 40 which has a stem 7, secured by means of a thumb-screw 8 in a post 9 at one end of the base or bed plate 1.

The sliding plunger-head 2 has a contracted forward end 10 and is forked at the rear end, 45 so as to form opposite wings 11, which carry a transverse pin 12, and upon the latter is mounted an antifriction-roller 13, which is adapted to a slot in a cam-lever 14, hung to a transverse pin 15, which is carried by cheek-

pieces 16 at the rear end of the base-plate, so 50 that when the said lever 14 is moved from the position shown in Fig. 1 to that shown in Fig. 2 the plunger-head 2 will be projected, reverse movement of the lever effecting a retraction of said plunger-head. 55

Screwing into a threaded opening in the base-plate is a set-screw 42, which serves as a stop to limit the descent of the operating-arm of the lever 14, so as to regulate the approach of the plunger 4 toward the plunger 6 60 to accord with the desired size of the tablet to be produced, and in addition to this adjustable stop there is a fixed stop 43, which prevents such movement of the cam-lever 14 as would cause the plunger 4 to come into 65 contact with and injure the plunger 6 when no charge of material was present between them.

The plunger-head 2 is contained between cheek-pieces 17 on the base-plate and is retained in position vertically by means of a transverse roller 18, carried by and free to turn in said cheek-pieces, but the plunger-head fits loosely between the cheek-pieces, the lateral position of said plunger-head being determined by means of set-screws 19, 70 adapted to threaded openings in forward extensions 20 of the cheek-pieces 17, these set-screws being on the opposite sides of the contracted forward portion 10 of the plunger-head, so that accurate lateral adjustment of the plunger 4 in order to bring it into line 75 with the tubular mold 5 can be readily effected.

The mold-head 3 has side arms 21, which 80 flank the post 9, carrying the fixed plunger 6, the outer ends of said arms 21 having a transverse pin 22, which is adapted to a slot 23 in a curved lever 24, the latter being hung to a transverse pin 25, carried by projecting 85 lugs 26 on the base-plate 1.

The mold-head 3 has an upwardly-projecting filling-hopper 27, which registers with the opening 28, formed in the upper side of the tubular mold 5, and mounted upon a stand 90 29 at one side of the machine is a measuring device consisting of a tubular casing 30, supporting a receptacle 30^a for the pow-

powdered or granular material and having an opening in the top through which the material can flow from said receptacle and also an opening in the bottom through which said material can be delivered into the hopper 27.

Free to turn in the casing 30 is a spindle 31, having a projecting stem 32 with operating-handle 33, the spindle being cut away at one side and having at said recessed side an adjustable slide 34, movable longitudinally on the spindle and adapted to be secured in position by means of a confining-screw 35, passing through a slot 36 in said spindle, so that by longitudinal adjustment of the slide 34 on the spindle the size of the pocket 37 for the reception of powdered material from the receptacle 30^a can be readily varied to accord with different requirements.

By turning the spindle 31 so that the pocket 37 is uppermost, as shown in Fig. 5, said pocket will receive material from the receptacle, and then by imparting a half-turn to the spindle the pocket will be carried to the lower position shown in Figs. 1 and 6 and will discharge its contents into the hopper 27, suitable stop-pins 38 and 39, carried, respectively, by the spindle 31 and tubular casing 30, serving to limit the rotative movement of the spindle.

It will be noted that the axis of the spindle 31 and tubular casing 30 are inclined in respect to the horizontal, and that the pocket 37 is at the depressed end of the spindle, so that the material will flow into and fill said pocket even when the latter is reduced to its least dimension, a result which could not be so effectively attained if the axis of the spindle 31 was horizontal.

In the operation of the device the powdered or granular charge is deposited in the tubular mold 5 while the parts of the machine are in the position shown in Fig. 1—that is to say, when the plunger-head 2 is retracted to its full extent and the mold-head 3 is fully projected. The lever 14 is then operated so as to project the plunger-head 2, the mold-head retreating before it and the lever 24 rising until the parts assume the position shown in Fig. 2. The powdered or granular mass is now confined in the mold between the movable plunger 4 and the fixed plunger 6 and may be subjected to any desired degree of compression by movement of the respective levers 14 and 24 in the direction of the arrows shown in said Fig. 2.

When the desired compression of the tablet has been effected, the plunger-head 2 is retracted by reversing the direction of movement of the lever 14, and there is also a retraction of the mold-head 3 until the parts assume the position shown in Fig. 3, whereupon the compressed tablet will be projected from the mold by the action of the fixed plunger 6.

When it is desired to change the character of the mold and plungers, the thumb-screw 8 is loosened so as to release the stem 7 of the plunger 6, and the latter is then moved for-

ward in the mold, so that the mold-head can be swung upward, as shown in Fig. 4, whereupon the plunger can be completely withdrawn from the mold, and the mold itself can be then removed upon slackening the thumb-screw 40, whereby it is held in position in the head 3, removal of the plunger 4 being effected by slackening the thumb-screw 41, 75 which secures the stem of said plunger in the plunger-head 2.

It will be observed that the fixed plunger 6 constitutes the guide for the mold 5 and mold-head 3, while the horizontal guidance of the plunger-head 2 is effected by the base-plate 1 and transverse roller 18, lateral guidance of said plunger-head being controlled by the set-screws 19. The roller 18 reduces the friction which might otherwise be due to upward pressure exerted upon the head 2 by the cam 14 when the latter is moved so as to project said head.

The only parts of the machine requiring careful machine-work are the mold and plungers, all of the other parts of the machine being capable of being fitted together without any further preparation than the simple cleaning of the castings, the boring out of the openings for the pivot-pins, and the threading of the openings for the set-screws, it having been the object of my invention to produce at small expense an effective machine intended for the use of druggists in preparing prescriptions, such use being, in most cases, infrequent and only for the treatment of small quantities of material at a time, and hence being such as to render the employment of expensive machines inadvisable.

Having thus described my invention, I claim, and desire to secure by Letters Patent—

1. A tablet-machine in which are combined a base or bed plate, a fixed plunger secured thereto, a sliding mold-head, a mold carried thereby and guided upon said fixed plunger, a sliding plunger-head, and a pair of hand-levers, one for reciprocating the mold-head and the other for reciprocating the plunger-head, substantially as specified.

2. A tablet-machine in which are combined a base or bed plate, a fixed plunger detachably secured thereto, a tubular mold adapted to slide on said plunger, a mold-head carrying the said mold and having projecting arms, an operating-lever and a pin through the medium of which the said lever is caused to act upon the arms of the mold-head, whereby the latter can on the release of the fixed plunger be swung upward away from the base or bed plate, substantially as described.

3. A tablet-machine in which are combined a base or bed plate, a fixed plunger, a tubular mold guided thereon, a mold-head carrying said mold and having projecting arms, a hand-lever engaging therewith and serving to impart movement to said mold-head, a plunger-head guided on said base-plate and carrying a plunger, and a hand-lever having

a cam which acts on said plunger-head and serves to reciprocate the same, substantially as specified.

4. A tablet-machine in which are combined a base-plate, a plunger-head supported thereon, side guides which do not vertically confine the plunger-head, a cam-lever acting on said plunger-head to project the same, and a transverse roller, bearing on said head and serving to prevent the same from being lifted as it is projected, said roller being removable from its bearings in order to free the plunger-head, substantially as specified.

5. The combination in a feeding device for tablet-machines, of a receptacle having a tu-

bular casing, a spindle adapted to rotate in said casing and recessed at one side, and a slide adapted to said recessed portion of the spindle and adjustable longitudinally thereon and combined with means for securing it 20 in position after adjustment, substantially as specified.

In testimony whereof I have signed my name to this specification in the presence of two subscribing witnesses.
